(57) **CLAIM**

The ornamental design for a first aid kit, as shown.

DESCRIPTION

FIG. 1 is a front perspective view of a first aid kit according to the design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a front elevational view showing the interior thereof. The broken line shown in FIG. 8 is for illustrative purposes only and forms no part of the claimed design.
